Primary Examiner — Cynthia Ramirez*Assistant Examiner* — Xavier Marti-Santos(74) *Attorney, Agent, or Firm* — Cantor Colburn LLP(57) **CLAIM**

The ornamental design for a perfume mixer, as shown and described.

DESCRIPTION

FIG. 1 is a front perspective view of a perfume mixer, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is front perspective exploded view thereof.

The broken lines illustrate portions of the perfume mixer, which form no part of the claimed design.

1 Claim, 6 Drawing Sheets(56)
